UNITED STATES PATENT OFFICE

97,030

DESIGN FOR AN AUTOMOBILE HEATER

Carl H. Will and Henry W. Fink, Minneapolis,
Minn., assignors to Tropic-Aire, Incorporated,
Minneapolis, Minn., a corporation of Delaware

Application July 17, 1935, Serial No. 57,706

Term of patent 7 years

To all whom it may concern:

Be it known that we, Carl H. Will and Henry W. Fink, both citizens of the United States, residing at Minneapolis, in the county of Hennepin and State of Minnesota, have invented a new, original, and ornamental Design for Automobile Heaters, of which the following is a specification, reference being had to the accompanying drawing, forming part thereof, and in which

Figure 1 is a front perspective view of an automobile heater showing my new design; and

Figure 2 is a rear perspective view thereof.

We claim:

The ornamental design for an automobile heater, substantially as shown.

CARL H. WILL.
HENRY W. FINK.
